UNITED STATES PATENT OFFICE.

MOSES MOSLER, OF NEW YORK, N. Y., ASSIGNOR TO THE MOSLER SAFE COMPANY, OF HAMILTON, OHIO.

FIREPROOF SAFE.

No. 824,373.

Specification of Letters Patent.

Patented June 26, 1906.

Application filed November 17, 1905. Serial No. 287,785.

To all whom it may concern:

Be it known that I, MOSES MOSLER, a citizen of the United States, residing at New York, New York county, New York, (post-office address care Mosler Safe Company, Hamilton, Ohio,) have invented certain new and useful Improvements in Fireproof Safes, of which the following is a specification.

This invention will be readily understood from the following description, taken in connection with the accompanying drawing, which is a horizontal section through the body of a fireproof safe exemplifying my invention.

15 In the drawing 1 indicates the casing; 2, the door-jamb; 3, the extension of the jamb-casting inwardly beyond the door-seat; 4, the general plane of the inner doorwork if the safe be provided with such; 5, the inner metallic box or lining, and 6 woodwork secured within the lining.

All of the parts thus far referred to are or may be constructed precisely as usual in this class of safes. In the usual construction of safes of this class the wall-space between the casing 1 and the lining 5 is usually filled with some indurating fireproof material—as, for instance, cement—filled into the wall-space in its damp state and always retaining more or less of its moisture. It may be referred to as “wet filling.” It is found that this wet filling has a serious distorting effect upon certain portions of the wall parts with which it lies in contact. The distortions are produced gradually, and it is believed the disturbing process is a continuing one. The plates of the outer casing bulge somewhat as a result of the disturbing influence of the wet filling; but the effect of this bulging is not serious except in an esthetic sense, for the casing-plates are comparatively thick and strong, and the bulging therefore slight, and there are no parts in contact with the casing-plates to be injuriously disturbed by the bulging; but with the lining 5 and the weaker portions of the jamb-casting the case is different. The inwardly-projecting portion 3 of the jamb-casting presenting, as it ordinarily does, a somewhat-extended stretch of comparatively thin and weak metal, is likely to be bulged inwardly, the result being that the inner doors become cramped and bound. Such doors if fitted snugly, as they should be, are often found to become later so

cramped as to require relief by filing at their 55 edges, and the proper relief having been given it is found that in course of time the doors become again bound and further relief is needed, and so on as time passes. The stepped portion 10 of the jamb-casting and 60 the extreme front of the door-jamb are not seriously subject to the evils in question, for the casting possesses great strength by reason of its form, and at the same time the body of filling is comparatively less than at 65 the plane portions of the safe-wall. Further, within the safe where the woodwork is located it is found that serious troubles arise. This woodwork is generally tightly fitted in place, and the inward bulging of the metallic 70 lining under the influence of the wet filling results in putting the woodwork under such strains and distortions that neatly-fitted drawers will not slide freely, and ultimately the joints of the woodwork become dislocated and the wooden partition-work becomes buckled to an unsightly degree. 75

My improvement is directed toward the remedy of the evils referred to.

Continuing with the drawing, 7 indicates 80 the filling as a whole, this filling occupying the entire space between the casing 1 and the inner metallic box or lining 5, this filling in the present case being of a composite character; 8, the outer and major portion of the filling, this portion coming against the casing, and being the usual wet filling, formed, say, of cement, and 9 the inner and minor portion of the filling, this portion coming next to the metallic box or lining 5 and being formed of 90 dry material, as asbestos or mineral wool. This dry filling 9 exerts no disturbing effect on the lining whatever may be the compressive effect received by it from the outer wet filling. It acts as a dry cushion between 95 the wet filling and the inner metallic box or lining 5. This dry filling is carried forward far enough to protect the inward extension 3 of the jamb-casting, the result being that the wet filling exerts no injurious influence upon 100 either the interior woodwork or the seating of the inner doorwork.

Safes of this class are generally provided with an externally-applied bottom or back plate for the casing, the filling being inserted 105 and the loose plate later applied. Numerous methods of procedure will suggest themselves to the experienced safe-constructo in

carrying out my invention; but my practical experience with the invention leads me to recommend that thin metallic walls 11 be employed between the two fillings, these 5 walls forming virtually a box whose walls are intermediate between the casing and the lining 5 and between the two fillings. These wall-plates having been properly placed, the dry filling may be applied between them and 10 the lining, and then the wet filling may be applied between them and the casing. It is to be understood, however, that this is merely an exemplifying mode of procedure in carrying 15 out my invention.

15 I claim—

1. In a fireproof safe, the combination, substantially as set forth, of a casing, a door-jamb portion therefor, an inward extension 25 therefrom, an inner metallic box or lining joining the inward extension of the door-jamb portion, a dry filler disposed exterior to the lining and the inner extension of the door-jamb portion, and a wet filler disposed exterior to the dry filler and between it and the casing.

MOSES MOSLER.
